UNITED STATES PATENT OFFICE.

JAMES C. NEWLIN, JR., OF BRYN MAWR, PENNSYLVANIA.

WATCH HOLDER.

Application filed October 15, 1926. Serial No. 141,763.

My invention relates to means for enclosing and supporting a watch or other time-piece, and has for its primary object to provide a device of this character which may 5 be readily applied to a suitable supporting surface, such as the dashboard or windshield of an automobile, airplane, trolley car or the like, to support the time piece in a convenient position in which it is readily visible.

Another object of the invention is to provide a watch holder which may be easily and quickly attached to the supporting surface without marring or otherwise disfiguring it, as is the case when screws or similar fastening devices are employed, and which, when applied, will be firmly held in position against displacement.

A further object of the invention is to provide a device of this character within which the watch may be conveniently assembled and yieldingly held in operative position, and in which the attaching means are entirely housed within the casing when the holder is applied to the supporting surface, so as to be hidden from view and protected from being tampered with, as well as against accidental injury.

A still further object of the invention is to provide a watch holder which is simple and efficient in construction, which may be easily and cheaply manufactured, and which consists of but few parts, and is not likely to get out of order.

With these and other objects in view, my invention comprises the various novel features of construction and arrangement and the combinations of parts hereinafter described, and pointed out in the appended 40 claims.

In the accompanying drawing illustrating one embodiment of the invention, and in which similar letters of reference are used to indicate similar parts,

Fig. 1 is a front elevation of my improved watch holder, showing a watch in position within the same and the holder applied to a supporting surface;

Fig. 2 is a rear elevation of the device detached from its supporting surface;

Fig. 3 is a vertical section of the line 3—3 of Fig. 1, also showing in dotted lines the positions of the parts when the suction cup is being compressed against the supporting 55 surface.

Fig. 4 is a horizontal section of the line 4—4 of Fig. 1, and

Figs. 5 to 10 inclusive are detailed views of parts or portions of the device.

The watch holder comprises a casing 1, 60 which is preferably cylindrical in cross-section and is of a suitable size to receive and contain a watch or other time piece. The front of the casing is formed with a slight opening 2, through which the face or dial 65 of the watch is exposed to view. Surrounding this opening, the casing is formed with an inwardly directed flange 3, which constitutes an abutment for the watch to limit its forward movement.

The casing is open at its rear or back to permit the insertion or removal of the watch, and is formed in its periphery with an opening 4 to accommodate the watch stem and afford it limited play. This opening is preferably of key-hole shape and extends lengthwise of the casing with its narrow portion toward the front. The rear or wide portion of the opening 4 is of a size to permit the head of the stem to pass freely 70 therethrough when the watch is being inserted in, or removed from the holder, while the narrow portion of the opening is adapted to receive the lower portion of the stem when the watch is moved forwardly in the 75 casing into its operative position, in which it bears against the flange 3.

At an intermediate point the casing 1 is preferably stepped as indicated at 5, so that its rear or back portion is of greater diameter than the front portion of the casing in 80 which the watch is contained. While this arrangement is not essential, it is desirable since it not only adds to the appearance of the device, but provides a base having a 85 broad bearing upon the supporting surface to which the holder is applied.

A member or cross piece 6, is received within and removably secured across the casing behind the watch, in any suitable 100 manner. In the present embodiment of the invention, this member is in the form of a bow spring which extends substantially diametrically across the casing and is bowed toward the front of the same. The free ends 105 of member 6 are adapted to be interlocked with a pair of lugs or ribs 7 projecting inwardly within the rear portion of the casing in diametrically opposite relation. This is accomplished by rotating the member with 110

its free ends depressed, so as to engage the same under, that is, in front of the lugs. To insure against the accidental displacement of the member 6, means are preferably provided for retaining it against rotation. To this end the casing may be formed adjacent each lug with a projection or stop 8 which extends slightly forwardly therefrom, and is adapted to be received in a notch 9 in the 10 corresponding extremity of the member.

When thus secured in position the member 6 not only serves to retain the watch within the case, but is so flexed that it is held under tension and exerts a forward 15 spring pressure which is transmitted to the watch yieldingly to support the same within the casing in its operative position against the flange 3.

The member 6 also forms a yielding support for a resilient suction cup 10, which may be formed of rubber or other suitable material. The suction cup is mounted substantially centrally on the member and is preferably secured thereto by being formed 25 with a forwardly projecting head 11 having a transversed slot 12 through which the member 6 passes, and in which it is frictionally held. The head terminates in a flat bearing face 13 adapted to contact substantially centrally with the back of the watch case to provide a cushion between the latter and the member 6, whereby to assist in absorbing vibration and shock and also to transmit the spring pressure of the member 30 to the watch without any danger of scratching or otherwise marring the same.

The body of the suction cup faces rearwardly and preferably projects slightly through and beyond the open back of the 40 casing. The suction cup may be of any well-known or suitable form so that when pressed against a supporting surface it will adhere thereto by means of a vacuum or partial vacuum created within the cup.

From the foregoing description the manner of assembling the watch within the holder will be obvious.

To apply the holder to a supporting surface, the rear edge of the casing 1 is pressed manually against the same, thereby slightly compressing the suction cup. Pressure is then applied to the watch crystal, which is preferably unbreakable and is exposed through the sight opening 2, to shift the 50 watch rearwardly in the casing against the spring action of the member 6, the opening 4 affording sufficient play for the watch stem so as not to interfere with this movement. This projects the suction cup rearwardly 55 and further compresses it against the supporting surface. The pressure is then removed from the watch crystal, whereupon

the spring member 6 restores the watch to its normal or operative position, at the same time exerting an outward or forward tension on the cup to increase the suction therein and cause the cup to obtain a firmer grip and adhere securely to the supporting surface to retain the holder in the desired position. The spring member 6 also reacts upon the casing 1 to press the rear edge thereof against and hold it in firm contact with the supporting surface to steady the holder and prevent it from wobbling. When the holder is thus applied, the suction cup is entirely 70 housed within the rear portion of the casing and hidden from view. This not only enhances the appearance of the holder, but prevents the suction cup from being tampered with, and protects it from accidental 75 injury.

It will be understood that various changes may be made in form, arrangement and combination of the parts without departing from the spirit of the invention defined in the 80 appended claims.

Having thus described my invention, I claim and desire to protect by Letters Patent of the United States—

1. A watch holder comprising a casing 90 open at its back for the insertion of a watch and formed in its front with a sight opening therefor, a spring member extending across and having an interlocking engagement with said casing to retain a watch 95 therein, said member being adapted to exert forward pressure on the watch to yieldingly support the same adjacent said sight opening, and a suction cup for supporting said casing, carried by said spring member.

2. A watch holder comprising a casing open at its back for the insertion of a watch, a member extending across and detachably engaged with said casing to retain a watch 105 therein, and a suction cup for supporting said casing, carried by and projecting rearwardly from said member and having a resilient head mounted on said member and also adapted to bear against a watch within 110 said casing.

3. A watch holder comprising a casing open at its back and formed in its front with a sight opening to expose a watch, a suction cup for supporting said casing, substantially housed within the rear portion 115 thereof, and means mounted within said casing for both yieldingly supporting said suction cup and yieldingly supporting a watch within the casing adjacent said sight opening.

In testimony whereof, I have signed my name to this specification.

JAMES C. NEWLIN, JR.
